UNITED STATES PATENT OFFICE.

ROBERT H. HAWKINS, OF NEW HAVEN, CONNECTICUT; HENRY G. NEWTON,
ADMINISTRATOR OF SAID ROBERT H. HAWKINS, DECEASED.

SEWING-MACHINE.

SPECIFICATION forming part of Letters Patent No. 316,263, dated April 21, 1885.

Application filed April 24, 1882. (No model.)

To all whom it may concern:

Be it known that I, ROBERT H. HAWKINS, of New Haven, in the county of New Haven and State of Connecticut, have invented new 5 Improvements in Sewing-Machines; and I do hereby declare the following, when taken in connection with accompanying drawings and the letters of reference marked thereon, to be a full, clear, and exact description of the 10 same, and which said drawings constitute part of this specification, and represent, in—

Figure 1, a front view of so much of the machine as will illustrate the invention; Fig. 2, an 15 under side view of the same; Fig. 3, an end view, looking toward the shuttle-race; Fig. 4, a sectional view of the race and shuttle-driver; Fig. 5, a perspective view of one shuttle detached; Fig. 6, a transverse section through the rock-shaft D, showing the grooved arm J of the 20 rock-shaft F and its connection with the rock-shaft D; Fig. 7, an end view of the shuttle and driver, showing the driver in its extreme rear working movement; Fig. 8, a side view of the arms J and K, showing the hinged wall of 25 the groove turned away to release the arm K; Fig. 9, the same as Fig. 7, showing the additional movement of the driver when the groove J' is opened.

This invention relates to an improvement in 30 that class of sewing-machines employing a vertically-reciprocating needle and an oscillating shuttle, the object of the invention being to adapt the machine to the working of two or more needles and corresponding shuttles by a 35 single mechanism, and is specially adapted to the machine known as the "Singer machine," the parts of which pertaining to this invention are shown in the accompanying illustrations; and the invention consists in the construction as hereinafter described, and more 40 particularly recited in the claim.

A represents the needle-bar, to which a vertical reciprocating movement is imparted by the usual mechanism employed in sewing-machines of this class, too well known to require illustration or description.

The head B of the needle-bar is constructed to receive two or more needles (here shown as two, a a,) parallel to each other and distant 45 from each other according to the distance required between two lines of stitches to be run,

the needles being common sewing-machine needles, both alike.

Upon the under side of the bed C the shuttle shaft D is arranged, in the usual manner, 55 in bearings E E. An oscillating movement is imparted to this shaft from the driving-shaft above through a rock-shaft, F, hung in bearings G G beneath the bed of the machine. The connecting-rod H, from the eccentric on the 60 driving-shaft above, is attached to an arm, I, on the front side of the rock-shaft.

On the opposite side of the shaft is an arm, J, which engages a crank-like arm, K, on the shaft D. The rocking or oscillating movement of the shaft F is therefore communicated to the shaft D. The pin L on the crank K works in a groove, J', in the arm J of the crank-shaft F, as seen in Fig. 6, and substantially as in the Singer machine. 70

To the opposite end of the shaft D the shuttle-driver M is attached so as to partake of the oscillating movement of the said shaft D. This shuttle-driver is substantially the same as in the Singer machine, except as hereinafter described. 75

The shuttle employed is that known as the "Singer oscillating shuttle."

The shuttle-race is circular, concentric with the shaft D, as seen in Fig. 3. The one part, 80 N, is made fast to the bed. The other part, O, is hinged to the part N, as at b, and so that the movable part O may be turned from the fixed part N, as seen in broken lines, Fig. 3. The two parts, when the race is closed, are secured together by a latch, P, or other suitable mechanism. The internal face of the shuttle-race is constructed with two grooves, d d, parallel with each other and in a plane at right angles to the axis of the shaft D. These grooves 85 correspond in shape to the rib e on the back of the shuttle. (See Fig. 5.) This back of the shuttle is the segment of a circle corresponding to the interior of the shuttle-race and so as to follow the grooves d in the oscillation of 90 the shuttle-driver. The two grooves d d (see Fig. 4) support the two shuttles in their proper relation to their respective needles, substantially as the one is usually supported, and so that the two work in planes parallel to the 95 path of their respective needles.

The shuttle-driver M differs only from that

in the Singer machine in that it is extended, as seen in Fig. 4, to reach the second shuttle, the two shuttles being shown in said figure in their proper position in the shuttle-race, and 5 through the shuttle-driver are annular slots *f f*, through which the needles work in the same manner as in the single slot of the driver in the Singer machine. In the Singer machine the bobbin is removable from the shuttle without taking the shuttle from its race; but where 10 two shuttles are employed this cannot be done; hence the necessity of making the shuttle-race so as to open, in order that the inside shuttle or shuttles may be removed from the race to 15 replace or adjust the bobbin.

In the ordinary working of the machine the shuttle-driver in the extreme rear position—that is, the position which carries the shuttles to their extreme rear position, as seen in Fig. 20 7—will not free the shuttles so that they can be removed from the race when the part *O* is dropped, as seen in that figure. The extreme movement of the arm *J*, when the shuttle-driver stands in this position, is seen in solid 25 lines, Fig. 6. In order to give a farther movement of the shuttle-driver in the direction of the rear movement of the shuttles, the outer wall, *R*, of the groove *J'* is constructed separate from the arm *J*, and hinged thereto, so 30 that it may be turned to one side, as seen in Fig. 8, leaving the crank-pin *L* exposed, and when so exposed the arm *K* may be turned outward, as seen in broken lines, Fig. 6, giving to the shuttle-driver a farther rear movement, and so that its heel will clear the shuttles, as seen in Fig. 9, and permit their 35 removal from the race, or their introduction, as the case may be, and when introduced the arm *K* is returned to take the pin *L* into the slot.

Then the hinged wall *R* of the slot is returned, 40 as seen in Figs. 1, 2, and 6.

If more than two lines of stitches are desired to be run, then as many needles are provided as lines of stitches are required, and shuttles accordingly. In such case the shuttle-race will be constructed with grooves corresponding to the number of shuttles, and the driver extended to embrace the several shuttles, and also provided with slots corresponding 45 to the respective needles.

Sewing-machines have been constructed with two or more needles, whereby parallel lines of stitches are produced. Therefore no claim is herein broadly made to a sewing-machine so constructed; but

50

55

What I claim is—

In a sewing-machine, the combination of a needle-bar carrying two or more needles, a circular shuttle-race constructed with guides for two or more shuttles, a shuttle-driver, *M*, 60 arranged upon a rock-shaft, *D*, concentric with the shuttle-race, the said shuttle-driver constructed with slots corresponding to the respective needles, two or more oscillating shuttles arranged in said race, the shuttle-race divided, one part stationary, the other hinged thereto, whereby said race may be opened, the rock-shaft *D*, provided with a crank, *K*, and the rock-shaft *F*, carrying the arm *J*, the said arm constructed with a groove to receive the 65 crank-pin *L*, the outer wall of the said groove hinged to its arm, whereby said groove may be opened or closed, substantially as and for the purpose described.

ROBERT H. HAWKINS.
